Primary Examiner — Catherine Ho(74) Attorney, Agent, or Firm — Sughrue Mion, PLLC(57) CLAIM

The ornamental design for a label as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a label showing my new design; and,

FIG. 2 is a rear view thereof.

The dash-dot broken lines define the bounds of the claimed design and form no part thereof. The uniform broken lines show portions of the article that do not form part of the claimed design.
